UNITED STATES PATENT OFFICE.

EZRA M. DRAKE, OF NEW YORK, N. Y.

DESIGN FOR BAND-COMBS.

Specification forming part of Design No. **8,872**, dated December 28, 1875; application filed December 14, 1875.
[Term of Patent 7 years.]

To all whom it may concern:

Be it known that I, EZRA M. DRAKE, of the city, county, and State of New York, have invented a Design for Long Combs, of which the following is a specification:

The nature of my design is fully represented in the accompanying drawings, to which reference is made—

Figure 1 being a perspective view of the comb in its normal condition. Fig. 2 represents more clearly the configuration of the comb as it would appear if straightened out.

My said design relates to what are commonly known as "long combs" or "band-combs."

A is the back, and B the teeth, of the comb. The end portions *a b* of the comb have their back and teeth parts more or less straight, or moderately curved, as more plainly shown in Fig. 2; but the central portion *B'* sweeps or curves forward on the arc of a circle, or like curvature, as also more plainly represented in

Fig. 2. This forwardly-curved central portion *B'* of the comb has, preferably, its teeth somewhat shorter than those of the adjacent end portions *a b*, the ends of the teeth at such central portion being ranged on a curve, as shown at *b'*, while the curve described by the back of said central portion is formed on a shorter curve or arc, as at *c'*; but I do not consider the mere shortening of the teeth of the forwardly-curved central portion *B'* of the comb as essential to my design.

What I claim as my invention is—

The design for long combs, in which the central toothed part *B'* of the comb is curved forward, and the general configuration substantially in the manner described, and illustrated in the accompanying drawings.

EZRA M. DRAKE.
